METAL SHINGLE

Bertrand E. Carlson, Naperville, and Joseph Studer, St. Charles, Ill.

Application May 14, 1931. Serial No. 537,232

7 Claims. (Cl. 108—17)

This invention relates to improvements in metal shingles.

One object of the invention is to provide a metal shingle for roofs that may be laid with others in stepped offset rows in simulation of the usual wood shingles.

Another object of the invention is to provide a metal shingle arrangement which is thoroughly weather tight; economical to manufacture; easy to lay by the use of ordinary nails and without any extra clips or the like such as heretofore commonly employed.

Other objects of the invention will more clearly appear from the description and claims hereinafter following.

In the drawing forming a part of this specification, Figure 1 is a plan view of a portion of a roof showing my shingles applied thereto. Figure 2 is an enlarged, vertical, sectional view 20 corresponding to the line 2—2 of Figure 1. Figure 3 is a sectional view corresponding to the line 3—3 of Figure 2. Figure 4 is a sectional view, corresponding to the line 4—4 of Figure 2. Figure 5 is a broken, elevational view of a portion of the lower exposed end of a shingle. And Figure 6 is a broken, perspective view illustrating a locking arrangement between two of the shingles.

In said drawing, the shingles are shown as 30 formed of sheet metal arranged in horizontal rows with one row offset a half length of shingle with respect to the next adjacent upper and lower rows. In carrying out the invention, each shingle has a main flat portion or panel 10 provided along its lower horizontal edge with a straight flange 11 of a width corresponding to the desired amount of stepping between the adjacent rows of shingles. Said flange 11 is arranged at right angles to the main panel portion 40 10, as clearly illustrated in Figure 2, and at one end, the lefthand end as viewed in the drawing, will be outwardly offset as indicated at 111, the thickness of the metal to provide for the overlap joint which occurs as shown best in 45 Figure 4. Along its lefthand side, as viewed in the drawing, each shingle is provided with a flange 12 bent or folded under the main panel portion and slightly spaced therefrom so as to provide a groove or recess for the reception of 50 a complementary flange 13. Each shingle, along its righthand edge or side will be provided with a flange 13, which, as shown, is formed by bending or folding the metal back upon itself on the upper side thereof, and will be normally spaced 55 from the main or panel portion 10 a distance

to snugly receive the flange 12 of the next adjacent shingle. As will be apparent from Figure 3, a lock joint is provided along the side edges of each pair of shingles in the same row by sliding the same one toward the right and 60 the other toward the left, relatively.

Along its top edge, each shingle is provided with an approximately semi-circular, upwardly extending flange 14, the concave face of which faces downwardly or toward the lower edge of 65 the shingle, when in position, as shown in Figure 2. Said semi-circular or curved flange 14 will be of such height and extent that the top or free edge thereof will extend forwardly and preferably engage the inner face of the flange 11 of 70 the next higher shingle or shingles at a point approximately three fourths of the height or width of the flange 11. As will be seen from Figure 2, the curved flanges 14, which are underneath the shingles of the next higher row, serve 75 a very important function, in that, any rain, sleet or the like which may be driven under the flanges 11, will be deflected upwardly and thrown back against the inner faces of the flanges 11 and cannot enter beneath the shingles of the 80 next higher rows or become trapped. In other words, a chamber is formed by the curved flanges and straight flanges 11, which serves to automatically destroy the momentum of any rain or other foreign matter that may be driven upwardly between the shingles and the rain or the like will then drip or drain outwardly from beneath the flanges 11.

To secure the shingles in place, the righthand edges of each of the shingles, within the folded 85 flange portions and outwardly of the actual lock joint between two shingles, are provided with circular depressions 15—15, which are perforated so as to receive the shanks of nails 16 therethrough, as shown. As will be evident, the 90 nails are entirely covered or protected by the overlapping adjacent shingles, as shown in Figure 3.

As an additional means of locking the shingles together, particularly the lefthand edge of each 100 shingle with respect to the righthand nailed edge of the underlying shingle with which it is interlocked, the following means are provided. Each curved flange 14, near its righthand end, and for a distance equal to or slightly greater than 105 the width of the lock joint, will have a narrow downturned flange 17 at the free edge thereof and the lefthand end of each flange 14 will be slightly cut back, as indicated at 18, so that its free edge will engage behind the downturned 110

flange 17. With this arrangement, when two shingles in the same row are interlocked, as shown best in Figure 3, along their side edges, their top edge curved flanges 14 will also be 5 interlocked for a short distance by the construction indicated at 17 and in Figure 6.

In order to permit of one row of shingles being offset half the width of a shingle with reference to the adjacent rows, and to prevent gaps between the flanges 11 and panels of the next 10 lower row of shingles where the lock side joints occur, each flange 11 will preferably be notched at its lower edge at the center thereof, as indicated at 19, for a depth, corresponding to the 15 thickness of the locked joint and the edge of the flange 11 to the right of the notch, as best indicated in Figure 5, will be sloped back toward the right until it becomes alined with the normal straight edge 211 of the flange 11.

20 In applying the shingles, the same is done from left to right in the same row. A shingle is put in place and is nailed along its right edge, which is then exposed. To accomplish this in an easy manner and to prevent buckling of the shingle, a special block may be employed, corresponding to the slope of the shingle and slope of the roof, which is inserted temporarily under the righthand edge of the shingle so as to support said edge while the nails are being driven home. Such block will be suitably slotted in line 25 with the nail holes so that the nails may be properly driven and the block then withdrawn. After one shingle is nailed in place, the next shingle in the same row is then slipped over the nailed shingle and moved to the right with 30 respect thereto, until the lock joint is obtained, shown in Figure 3, thus covering the nails of the first applied shingle. The succeeding shingles in the same row are then secured in place in 35 the same manner. After one row of shingles is applied, the next lower row is started. Beginning at the left, the first shingle in the next lower row will have its curved flange 14 hooked under the flange or flanges 11 of the next higher 40 row and the shingle then swung down into its proper position and then nailed. The next shingle in the same row is then applied in a 45 similar manner and interlocked, as will be understood.

50 With the construction shown, it is evident that the shingles when applied, have the stepped and staggered appearance of ordinary wood shingles. Furthermore, no rain or the like can pass beyond the curved flanges 14, as previously pointed 55 out. The nails are entirely concealed and hence danger of corrosion at the nail holes is eliminated and secure, tight, weather-proof joints are formed along the interlocked side edges of adjacent shingles. The shingles may be easily 60 manufactured; shipped in stacked formation; and no special clips or the like are required so that the same may be applied by the average person without special tools.

Another important advantage of the construction described resides in the particular manner 65 of securing the shingles along their side edges. As clear from inspection of Figure 3, when the nails 16 have been put in place with the side edge of the shingle gauged by the gauge block 70 hereinbefore referred to, and the next adjacent shingle overlapped and interlocked with the nailed shingle, the nail and its head function to not only retain but to support both interlocked edges of the shingles in elevated position with 75 respect to the underlying support. The right

hand shingle 10, as viewed in Figure 3, cannot be depressed beyond engagement with the nail head and consequently, because of the interlocked joint with the lefthand shingle 10, the latter cannot be depressed so long as the interlocked joint remains intact. Hence, each shingle is positively supported around all four of its edges and the shingles, when laid, are thereby rendered stiff and rigid notwithstanding that, the shingles may be rather flexible considered 80 individually and when unsecured.

85 Although there has been shown and described what is now considered the preferred manner of carrying out the invention, the same is by way of illustration only and all changes and modifications are contemplated that come within the scope of the claims appended hereto.

90 What is claimed is:

1. A metal shingle having a curved flange along its top edge, a downturned flange along 95 its bottom edge and complemental interlocking sealing-formations along the respective side edges, said shingle along one of its side edges being provided with a plurality of apertures disposed outwardly of the adjacent sealing-forma- 100 tion for reception of securing nails, said apertures and said nails being adapted to be covered by an adjacent shingle in the same row when assembled and interlocked therewith.

2. A metal shingle having an upwardly ex- 105 tended curved flange along its top edge, a downturned flange along its bottom edge, and complemental locking flanges along its side edges, the shingle being apertured along one of its side edges to receive a fastening device, the aperture 110 being concealed when said shingle is assembled with a corresponding shingle in the same row.

3. A metal shingle having a flange along its upper edge curved upwardly and then forwardly 115 to provide a deflecting wall, a downturned flange along its bottom edge, and reversely disposed folded-over, locking flanges along its side edges, whereby two adjacent shingles in the same row are adapted to be interlocked and one overlap the other, one edge of the shingle adapted to 120 assume the interlocked position being apertured outwardly of the lock joint, to receive a securing device whereby, when the securing device is in place and the corresponding interlocked joint effected, both side interlocked edges will be sup- 125 ported by said device.

4. A metal shingle having a flange along its top edge curved upwardly and thence forwardly, the free edge of said flange at one end thereof having a supplemental inturned narrow flange, 130 and, at its other end, being complementally cut away, said shingle having a downturned flange along its bottom edge, a folded over flange along one of its side edges, and a folded under flange 135 along its other side edge, the edge of the shingle having said folded over flange being apertured for the reception of a securing device.

5. A metal shingle having a downturned flange along its bottom edge, complemental sealing- 140 formations along the respective two side edges, and a flange along its top edge extended upwardly and forwardly and the free edge of which is adapted to engage behind the downturned flange of a corresponding shingle in the next higher 145 row, one side edge of said shingle being also provided with means adapting it to be secured to and supported in spaced position above an underlying support.

6. A sheet metal shingle adapted to be laid in rows with like shingles, said shingle compris- 150

ing: a main panel; a weather-sealing integral formation along its upper edge cooperable with a bottom edge structure of a similar shingle in the next higher row; an integral downturned flange 5 along the bottom edge of the panel whereby the panel is disposed at an angle to the underlying support; and complemental interlocking formations along each side edge of the panel, one side edge being adapted to underlie and the other 10 to overlie adjacent like shingles in the same row, said underlying edge being formed, outwardly of the interlocking portion thereof, for the reception of headed securing nails prior to the assembling of the next adjacent overlying shingle 15 whereby when said next adjacent overlying shingle is applied and interlocked, the headed nails are concealed and both interlocked edges supported thereby in spaced relation to the underlying support.

20 7. A sheet metal shingle adapted to be laid in rows with like shingles commencing with a top

row, said shingle comprising: a main panel; complemental interlocking sealing formations along the respective side edges of the panel; a down turned flat butt flange along the bottom edge of the panel; and an approximately semi-circular flange along the top edge of the panel, the concave face of said semi-circular flange facing toward the bottom edge of the panel and the free edge of said semi-circular flange being adapted to engage the inner face of the bottom edge butt flange of a similar shingle in the next higher row and form therewith a chamber for destroying the momentum of rain driven upwardly thereinto, the free edge of the bottom end butt flange being adapted to engage the top surface of the main panel of a similar shingle in the next lower row and permit drainage of rain from behind said butt flange.
